UNITED STATES PATENT OFFICE.

RICHARD BRADSHAW, OF MONTREAL, QUEBEC, CANADA.

FOLDING COUCH-BED.

1,369,385.

Specification of Letters Patent. Patented Feb. 22, 1921.

Application filed February 10, 1919, Serial No. 275,996. Renewed January 19, 1921. Serial No. 438,529.

To all whom it may concern:

Be it known that I, RICHARD BRADSHAW, a subject of the King of Great Britain, and resident of the city of Montreal, in the Province of Quebec and Dominion of Canada, have invented certain new and useful Improvements in Folding Couch-Beds, of which the following is a full, clear, and exact description.

10 This invention relates to improvements in folding couch beds and the object of the invention is to provide a simple, inexpensive and durably constructed metal-frame couch bed which will provide storage space for 15 bedding during the day time.

A further object is to provide a couch bed so constructed that the spring is in two independent parts, thus making it extremely comfortable for two persons to sleep on.

20 A still further object is to provide a couch bed which may be operated with very great ease.

The device consists generally of a framework divided into three hingedly connected parts, one of which nests in another, while the third part covers the other two and forms the top of the couch by day. A mattress folded at its longitudinal center is mounted on a bed bottom fabric supported 30 in this upper or cover portion. The first named portion carries another section of bed bottom fabric, which is arranged in the form of a basket. When the couch is folded, the basket is in operative position and may 35 be used to contain the bedding during the day. When the couch is open for use, the basket is inverted and its bottom forms a support for the mattress.

In the drawings which illustrate the in-

40 vention;—

Figure 1 is an end elevation of the device in its folded position.

Fig. 2 is an end elevation illustrating the device in process of being opened.

45 Fig. 3 is an end elevation of the device arranged for use as a bed.

Fig. 4 is a perspective view of the device arranged for use as a bed with the mattress taken off.

50 Referring more particularly to the drawings, A, B and C represent the three main portions of the framework. The portion A comprises short front legs 11 and longer back legs 12 connected by horizontally disposed members 13. The legs and members 13 are connected by braces 14. As the legs

11 and 12 are of different lengths and all rest upon the floor, it will be obvious that the back legs 12 project farther upward than the front legs. The portion B of the framework includes front legs 15 of the same length as the back legs 12 of the part A and short back legs 16, which are pivotally connected at 17 to the upper ends of the front legs 11 of the part A. The legs 15 and 16 60 are connected by horizontally disposed members 18. Braces 19 are also connected between the legs 15 and 16 and the members 18. The legs 16 of portion B are pivoted inside the legs 11 of the portion A and the 65 whole of portion B is made somewhat shorter than portion A, so that when portion B is swung around the pivotal point 17, it will occupy a position inside portion A, as clearly shown in Fig. 1. The portion C 70 of the device includes a rectangular framework 20 pivoted near its rear edge to the upper extremities of the legs 12 at the point 21 and provided near its front edge with short legs 22, adapted to rest on the members 13 when the framework is disposed in a horizontal plane. Braces 23 may be connected between the legs 22 and the framework 20. A bracket 24 is connected near the bottom of one or both of the legs 12 and 80 a similar bracket 25 is connected to the rear edge of the framework 20. A helical spring 26 is connected between the two brackets. It will be noticed that both of these brackets are to the rear of the pivotal point 21, 85 so that when the framework 20 is in horizontal position, as shown in Figs. 1 or 3, the brackets are farther apart than when the framework is in the vertical position shown in Fig. 2. It will thus be seen that 90 the spring 26 is in tension when the frame 20 is horizontally arranged, so that when the frame is raised to the position shown in Fig. 2, the spring 26 will assist in lifting it and will also serve to hold it in vertical position, owing to the disposition of the bracket 25 and the engagement of the ends of the members 20 with the legs 12 holding the part C against movement past the vertical position by action of the springs. Any 100 suitable bed bottom fabric 27 is stretched in the frame 20 and forms a support for the whole of the mattress 28 when the couch is folded, as in Fig. 1, or for half the mattress when the couch is arranged as in Fig. 3. 105

55 A basket 29 of bed bottom fabric is mounted in the frame portion B and is so

arranged that when the device is folded, as in Fig. 1, the basket is available to hold bedding and when the device is arranged as in Fig. 3, the basket is inverted and its bottom forms in effect a continuation of the bed bottom fabric 27 and serves to support one half of the mattress. The mattress 28, which is of the construction ordinarily used in couches of this character, is folded 5 at its longitudinal center line and is provided with a valance 30, which in the day time hangs in front of the couch.

The operation of the couch is extremely simple. When it is desired to convert it 15 from a couch, as shown in Fig. 1, to a bed, as shown in Fig. 3, the frame 20 carrying the mattress is raised to vertical position, as shown in Fig. 2. This movement is assisted by the spring 26. As the frame 20 is raised, 20 the valance falls of itself to the position shown in Fig. 2. The bedding is then removed from the basket 29 and the frame B lifted or swung forwardly out of the frame A until the legs 15 rest on the floor. The 25 portion C is then lowered to its original horizontal position, the legs 22 resting on the members 13. As this motion is proceeding, the valance 30 falls naturally along the side of the inverted basket 29 to the position 30 shown in Fig. 3, and is thus guarded against creasing. The mattress is then opened out and the bed made up in the usual manner. When the bed is to be folded to couch form, the motions are reversed. When folded as 35 a couch, the legs 15 of the part B are supported on the frame 13 by lugs 31 provided on the legs. It will be noted that the legs 15 are offset at 32 near their lower extremities, so as to clear the frame 20 when the 40 device is folded as a couch.

Having thus described my invention, what I claim is:—

1. In a couch bed, a pair of independent bottom fabric sections, one section being invertible under the other and marginal extensions of said invertible section forming with the main portion a basket adapted to hold bedding and the like during the inverted position of the section.
2. In a couch bed, a central frame, and a pair of supplementary mattress supporting frames hingedly connected at opposite longitudinal edges of the central frame, one of said supplementary frames being adapted to swing within the central frame and including legs positioned to support its free edge on the central frame in swung-in position

and feet projecting beyond said legs adapted to support it on the floor when in swung-out position, and the second supplementary 60 frame including legs at its free edge to support it on the central frame.

3. In a device of the class described, a central frame, and a pair of supplementary frames hingedly connected at opposite longitudinal edges of the central frame, one of said supplementary frames being adapted to swing into the central frame, a basket of bed bottom fabric mounted in said supplementary frame positioned when the frame 70 is in swung-in position to hold bedding and when the frame is in swung-out position to be inverted and form a mattress support, and a bed bottom fabric mounted in said second supplementary frame in position to 75 occupy the same horizontal plane as the bottom of the basket of the first supplementary frame when the latter is in swung-out position.

4. A folding couch bed comprising a main 80 central frame provided at one side with relatively long legs extending above and below the frame and at the opposite side with relatively short depending legs, a supplementary side frame provided at one side with 85 relatively short depending legs pivoted at their lower ends to the upper ends of the short legs of the central frame, said supplementary frame being provided at the opposite side with relatively long depending legs 90 of substantially the same length as the long legs of the first frame, and the second supplementary side frame having one side pivoted to the upper ends of the long legs of the first frame and the opposite sides provided 95 with short depending legs adapted to engage the end portions of the central frame to support said second supplementary frame in horizontal position with its upper surface in a plane with the corresponding surface of 100 the first supplementary frame.

5. An arrangement according to claim 4 in which the first mentioned supplementary frame is foldable in a position beneath the second supplementary frame and within the 105 central frame and has the longer legs thereof provided with feet offset to clear the second supplementary frame and presenting projections engageable with the central frame to support therein the free edge of 110 said mentioned frame.

In witness whereof, I have hereunto set my hand.

RICHARD BRADSHAW.
